UNITED STATES PATENT OFFICE.

WILLIAM E. WADE, OF JOKER, WEST VIRGINIA.

SADIRON.

Application filed July 11, 1924. Serial No. 725,421.

To all whom it may concern:

Be it known that I, WILLIAM E. WADE, a citizen of the United States, residing at Joker, in the county of Calhoun and State 5 of West Virginia, have invented certain new and useful Improvements in a Sadiron, of which the following is a specification.

This invention relates to new and useful improvements in sad irons and has for its 10 principal object to provide a means whereby the handle therefor may be attached to or detached from the iron at will, so that one handle will serve for a number of irons, and need not be placed upon the fire with 15 the iron when the latter is being heated.

Another important object of the invention is to provide a sad iron and a handle therefor wherein the latter may be readily and easily disengaged from the body of the iron, 20 means being further provided for preventing the accidental disengagement of a handle from the iron.

A still further object of the invention is to provide a sad iron of the above mentioned 25 character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout 35 the same:

Figure 1 is a longitudinal sectional view through the body of the iron showing the handle therefor in side elevation.

Figure 2 is a top plan view with parts 40 shown in section, and

Figure 3 is a detail sectional view taken approximately on line 3—3 of Figure 1.

In the drawing wherein for the purpose of illustration is shown the preferred embodiment of my invention, the numeral 1 designates the body portion of my improved 45 sad iron and provided in the upper surface thereof is the longitudinally extending cavity 2, the same being preferably arranged in the central portion of the iron. Arranged in the cavity 2 is the transverse lug or cross member 3 and the top thereof is adapted to lie substantially flush with the upper surface of the body of the iron in the manner more clearly illustrated in Figure 55 1 of the drawing. The purpose of the lug

will hereinafter be more fully described. Extending upwardly on the opposite side of the cavity 2 are the longitudinally extending guide ribs 4 and 5 respectively, the same being integral with the body 1 and the same are preferably inclined inwardly with respect to each other in the manner more clearly illustrated in Figure 3 of the drawing whereby a substantially dove-tailed 65 channel 6 is provided. Extending across the forward ends of the ribs 4 and 5 is the transverse rib 7 which is also formed integral with the body 1.

Carried by the handle 8 is the base plate 70 9 and the same has its side edges beveled as clearly illustrated in Figure 3 of the drawing whereby the same is adapted for slideable movement between the guide ribs 4 and 5 so that the plate will seat in the dove-tailed channel 6 over the cavity 2 thus preventing any possibility of the vertical displacement of the base plate from the body portion of the iron. The base plate is provided with a longitudinally extending opening or slot 10 and pivotally supported therein are the transversely extending pin 11 arranged adjacent the rear end of the base plate 9 and the tongue 12.

The forward end of the opening or slot 85 10 terminates in the beveled seat 13 for cooperation with the forward end of the tongue 12 in the manner clearly illustrated in Figure 1. The tongue 12 increases gradually in thickness toward its center 90 from the ends thereof and the central portion is provided with a notch 14 for cooperation with the lug or transverse member when the handle is in position on the body of the iron. The tongue 12 is adapted to have the 95 bottom portion thereof fitting in the cavity 2 and for normally holding the notch 14 in engagement with the transverse member 3 which is arranged in the cavity 2 so as to prevent the longitudinal sliding movement 100 of the base plate on the upper surface of the body of the iron, the forward portion of the handle 8 is provided with an inwardly extending projection 15 and a coil spring such as illustrated at 16 is disposed between 105 the projection 15 and the upper surface of the forward end of the tongue 12 in the manner also clearly illustrated in Figure 1.

In order that the tongue 12 may be actuated for disengaging the notch 14 from 110 engagement with the transverse member 3 whenever it is desired to remove or detach

the handle from the body of the sad iron, I provide the tongue with a knob 17 which may be readily grasped and by lifting the same upwardly against the tension of the coil spring 16, the tongue 12 will swing on the pivot 11 so as to cause the notch 14 to be brought out of engagement with the lug or transverse member 3 and permit the rearward sliding movement of the base plate.

10 In this manner the handle may be readily and easily removed from the sad iron so that the iron will be heated without necessitating the handle therefor being subjected to the heat from the fire.

15 The simplicity in which my device is constructed enables a single handle to be used for a number of irons and the construction thereof is such as to securely hold the handle in position on the body of the said iron 20 against accidental disengagement therefrom. Considerable time and labor will be saved by the employment of a handle of the above mentioned character in attaching or detaching the same from the body of the iron.

25 While I have shown the preferred embodiment of my invention, it is to be understood that various changes in the size, shape and arrangement of parts may be resorted to without departing from the spirit of the invention and the scope of the appended claim.

30 Having thus described the invention, what I claim is:—
A sad iron comprising a body having a

cavity in the upper surface thereof, a transverse lug arranged in the cavity, longitudinally extending guide ribs on the opposite sides of the cavity, a transverse rib extending across the forward end of the aforementioned ribs, the inner opposed sides of the longitudinal guide ribs being under cut 35 to provide a substantially dove tailed channel, a handle, a base plate carried thereby and adapted to fit in said dove tailed channels, said base plate having a longitudinally extending slot provided therein, a tongue 40 pivotally supported at one end in said slot, the bottom portion of said tongue increasing gradually in thickness toward its center, said central portion having a notch provided 45 therein for engagement with the transverse lug in the cavity to prevent the longitudinal sliding movement of the base plate and handle on the body of the iron, a projection on the forward portion of the handle, the same being disposed in spaced relation above 50 the forward end of the tongue, a coil spring interposed between the projection and the forward end of the tongue for normally holding the latter in engagement with the lug, and a knob on said tongue for permitting the retraction of the tongue from engagement with the lug whereby the base plate and handle may be disengaged from 55 the body of the iron.

In testimony whereof I affix my signature.

WILLIAM E. WADE.
